UNITED STATES PATENT OFFICE.

POOLE HARRISON, OF KANSAS CITY, MISSOURI, ASSIGNOR TO STANDARD OIL COMPANY, OF WHITING, INDIANA, A CORPORATION OF INDIANA.

APPARATUS FOR TESTING GASOLENE.

1,355,554.

Specification of Letters Patent. Patented Oct. 12, 1920.

Application filed December 4, 1919. Serial No. 342,354.

To all whom it may concern:

Be it known that I, Poole Harrison, a citizen of the United States, residing at Kansas City, in the county of Jackson and 5 State of Missouri, have invented a new and useful Improvement in Apparatus for Testing Gasolene, of which the following is a specification.

This invention relates to a gasolene testing 10 apparatus and is particularly adapted to be used in making comparative tests of the ignition qualities of various grades of gasolene and the like. It is fully described in the following specification and shown in the 15 accompanying drawings, in which—

Figure 1 is a perspective view of my device; Fig. 2, a wiring diagram of the electrical connection; Fig. 3, a plan view of my device with the cover removed; Fig. 4, a 20 vertical section on the line 4—4 of Fig. 3, and Fig. 5 a vertical section on the line 5—5 of Fig. 3.

I have illustrated as an embodiment of my invention a box-like structure having a floor 25 10, glazed sides and ends, 11 and 12 respectively, and a back wall 13 to which is hingedly mounted a cover 14. A partition 15 divides this box in two equal compartments A and B. This partition is carefully set 30 into the bottom and ends of the box and a U-shaped strip 14^a secured to the under side of the cover fits snugly over the upper edge of the partition so as to prevent the inter- 35 communication of gases between the two chambers.

The floors of these compartments are sloped somewhat toward the rear as shown in Fig. 5, where a spark plug 16 is inserted in the center of each compartment. The 40 45 spark plug casings are preferably grounded on the metal work of the box while the insulated spark plug terminals are connected by means of the wire 17 with any suitable source of high voltage electricity such as a battery 18, and the vibrator 19. The circuit is then completed through a key 20 and a wire 21 which is grounded at any convenient point on the box. A small porcelain receptacle 22 is placed in each of the 50 55 compartments and at equal distances from the spark plug.

The method of operation of this device is as follows: The spark plugs are adjusted so that when the key 20 is closed sparks of 55 equal intensity will be produced by each.

The cover 14 is raised and it is necessary that the two compartments are carefully aired out. Two containers having the samples of gasolene to be tested are brought near the table on which the testing device 60 is placed and a small amount drawn from each in a pipette, the charge from one pipette being placed in a receptacle 22 in the chamber A, while the charge from the other pipette is placed at the same time in 65 the receptacle 22 in the chamber B. It is very essential for a comparative test of this kind that the two charges placed in the receptacles from the pipette shall be of equal amount, and that they shall be placed there- 70 in at the same time.

The cover 14 is now lowered and the switch 20 closed. Sparks are produced from the two spark plugs 16, and the charge in compartment A is ignited, while the 75 charge in compartment B does not ignite. This shows that under the conditions of the test the gasolene in the compartment A is more volatile and more easily ignited.

Before the tester is again used for a test 80 of this kind the cover should be raised and an electric fan or similar means employed to rid the box of all burned and unburned gases, as even small particles of these would tend to influence the results of subsequent 85 tests.

While I have shown and described but a single embodiment of my invention, it is to be understood that it is capable of many modifications. Changes therefore in the construction and arrangement may be made which do not depart from the scope of the appended claims in which it is my intention to claim all novelty inherent in my invention as broadly as possible in view of the 90 95 prior art.

What I claim as new and desire to secure by Letters Patent is:

1. In apparatus of the character set forth, a plurality of similar compartments, means for exposing liquid fuel under the same conditions in each compartment and means for applying ignition equally to said compartments, whereby comparative tests may be made under substantially the same conditions on samples of liquid fuel in said compartments. 100 105

2. In apparatus of the character set forth, a plurality of similar compartments, means for exposing liquid fuel under the same con- 110

ditions in each compartment and means for applying ignition equally to each compartment, closures for said compartments and a window in each through which the ignition 5 may be observed, whereby comparative tests may be made under substantially the same conditions on samples of liquid fuel in said compartments.

3. In apparatus of the character set forth, 10 a plurality of similar compartments, means for exposing liquid fuel under the same conditions in each compartment and a spark plug in each compartment adapted to be energized by electric current of the same voltage, whereby comparative tests may be made 15 under substantially the same conditions on samples of liquid fuel in said compartments.

4. In apparatus of the character set forth, 20 a plurality of similar compartments, means for exposing liquid fuel under the same conditions in each compartment, and a spark plug in each compartment, said spark plugs being connected in parallel with each other and adapted to be energized by a common 25 source of electricity, whereby comparative tests may be made under substantially the same conditions on samples of liquid fuel in said compartments.

5. In apparatus of the character set forth, 30 a plurality of similar compartments, means for exposing liquid fuel under the same conditions in each compartment and the floor of each compartment sloping toward the ignition means, whereby comparative tests may be made under substantially the same conditions 35 on samples of liquid fuel in said compartments.

6. In apparatus of the character set forth, 40 a plurality of similar compartments, a receptacle on the floor at one end of each compartment, for holding fuel to be tested, and a spark plug in the other end, whereby comparative tests may be made under substantially the same conditions 45 on samples of liquid fuel in said compartments.

7. In apparatus of the character set forth, 50 a plurality of similar compartments, a receptacle on the floor at one end of each compartment, for holding fuel to be tested, and a spark plug in the other end of said compartments sloping toward the spark plugs, whereby comparative tests may be made under substantially the same conditions on samples of liquid fuel in said compartments.

POOLE HARRISON.
